UNITED STATES PATENT OFFICE

ALBERT E. PAGE, OF BROOKLYN, NEW YORK, ASSIGNOR TO SCOTT & WILLIAMS, INCORPORATED, OF NEW YORK, N. Y., A CORPORATION OF MASSACHUSETTS

TUCKING ATTACHMENT FOR KNITTING MACHINES

Application filed December 10, 1927. Serial No. 239,231.

My invention consists of an improved tucking attachment for knitting machines and more particularly an attachment adapted to produce tucking at different points on 5 a stocking circumferentially at varied courses. Thus in the accompanying drawing the invention is illustrated employed in the production of tuck stitches to imitate the narrowing marks at the calf of the leg and 10 also other tuck stitches to produce the appearance of crowfoot or clocks at the sides of the leg and foot of the stocking.

According to my invention tuck stitches are made by means of the provision of 15 needles with longer latches for knitting those wales in which the tuck stitches are to be made, in a manner similar to that shown and described in my prior Patent 1,367,425, dated February 1, 1921. The movable clearing 20 or tucking cam is operated so that at some courses all the needles will be moved to clear the stitches, and at other times the needles will be projected only far enough to clear the stitches on the short latch needles, and not those on the long latch needles. 25

The tucking cam in the present invention can be operated from two separate controls at independent times, one of the controls depressing the tucking cam during at least 30 one full revolution of the needle cylinder for the production of the two rows of distinguishing marks at the back of the leg, and the cam being depressed by other means at other times for a partial revolution of the 35 needle cylinder in such manner as to cause production of tuck marks by the clocking needles but not causing the narrowing marks needles to tuck.

In the accompanying drawings I have 40 shown my improved tucking attachment applied to the well known Scott & Williams type of revolving needle cylinder seamless hosiery machine, but it should be understood 45 that I do not limit myself to that type of machine.

In the drawings—

Fig. 1 is a side elevation of sufficient of a 50 seamless hosiery machine to illustrate the main elements of my invention;

Fig. 2 is an elevation showing the movable clearing cam;

Fig. 3 is a plan view of the clearing cam and the mechanism operating same; while

Fig. 4 is a front elevation of the mechanism shown in Fig. 1. 55

In the example illustrated in the drawings, the leading stitch cam 361 is used as the tucking cam, being pivoted at 361^a and rocked by a pin 361^b projecting to the exterior of the cam cylinder 271. This pin 361^b rests upon the outer end of a tucking lever 243 pivoted on the bed plate B of the machine (Fig. 3). There is a small coiled spring 244 tending to hold the clearing cam 361 in its downward position (Fig. 2). The other end of the tucking lever 243 is connected to an adjustable vertical rod 231, and it is the vertical movements of this rod which move the clearing cam. 60

The machine is equipped with needles having long latches and short latches, as shown in the above mentioned patent to Albert E. Page 1,367,425, and the movements of the clearing cam 361 are such that while both the long and short latch needles will clear their stitches when the cam is in its uppermost position, only the short latch needles will clear their stitches when the cam is in its lowermost position. In other words, tuck stitches will be produced on the long latch needles as long as the rod 231 is in its uppermost position. 65

For the purpose of making fashion marks such as shown in the Scott Patent 1,233,714, dated July 17, 1917, I prefer to place two long butt, long latch needles at the back of the stocking, the remainder of the needles on the heel side of the stocking being short butt needles with short latches. As in my earlier patent I set the clearing cam in tucking position by means of the pattern chain 85, a tripping device operated from the quadrant 75 causing the clearing cam to return to the plain knitting position at the proper time. These means for lowering the clearing cam for a minimum of at least one full revolution of a needle cylinder comprise a latch 237 pivoted to the lower end of the rod 231, whose catch engages the outer end 90

of a bracket 232 pivotally mounted on a stud 234 on the frame of the machine. The lower end of the rod 231 contains a slot 240, and in this slot moves a screw 239 mounted 5 on the bracket 232. When the latch 237 engages the upper side of the arm of the bracket 232 this screw is at the lower end of the slot. There is a tension spring 238 fastened to the end of the latch 237 which tends to 10 draw and thus hold the latch in engagement with the bracket 232, and also tends to draw the vertical rod 231 downwardly.

The bracket 232 has a depending arm 235 with a pin or stud 236 projecting laterally 15 from its end and overlying one side of the links of the pattern chain. When a lug on this side of the pattern chain comes in contact with the pin 236 it rocks the bracket 232, lifts the rod 231 and causes the clearing 20 cam to be lowered to the position shown in full lines in Fig. 2 where the long latch needles no longer clear their stitches and tucks are produced. For the purpose of tripping the rod 231 to prevent tucking on 25 more than two successive courses the following elements are provided in connection with the latch 237. There is a trip wire 242 carried by the latch 237 which can be adjusted at such a height that the free end of the trip rod 241 will be opposite the lower end 30 of the wire when the rod 231 is in elevated position. This trip rod 241 is pivoted on the usual quadrant 75 and slides back and forth through a notch in the bracket 232. 35 When the rocking of the quadrant pushes the rod 241 forward it hits the trip wire 242 if the clearing cam is in tucking position, and knocks the latch clear of the bracket. This permits the tension spring 238 to pull 40 the vertical rod 231 downwardly and the clearing cam 361 thereupon rises and tucking ceases. The points of pivotal connection to the quadrant 75 of the tripping rod 241 and the chain pawl 87 which acts on the 45 ratchet (not shown) to rack the chain, are such that for the most part the pawl and the rod move in opposite directions and the tripping rod has a longer movement than does the pawl. In the example shown in 50 the drawings the quadrant completes its cycle of movement in four revolutions of the needle cylinder and the tripping of the vertical rod 231 is timed to take place so that the clearing cam 361 will be returned to its 55 full clearing position on or before the completion of two revolutions after the bracket 232 is tipped upwardly by the lug on the pattern chain. When the pin 236 of the bracket 232 drops off the lug on the pattern 60 chain, the bracket swings back to its normal position, shown in Fig. 1, the screw 239 fastening the vertical rod to the bracket drops to the bottom of the slot 240 and the pivoted latch 237 reengages the bracket 232 65 as shown. Plain knitting will then continue

until another lug on the pattern chain comes along to rock the swinging bracket 232 and raise the rod 231 and lower the clearing cam 361 for tucking. This mechanism provides means for inserting for two courses the distinguishing marks referred to in the patent to Robert W. Scott, Number 1,233,714 dated July 17, 1917, and then omitting them for six or more courses during the knitting of those portions of the calf of the leg where such marks are desired. I have invented improved means which, in addition to producing the tuck stitches on the back of the calf of the leg, will also make other tuck stitches to produce the appearance of clocks at the side of the leg and foot of the stocking as shown in the patent to Robert W. Scott Number 1,311,623 dated July 29, 1919.

By my mechanism it is possible to produce the tuck stitches at the sides of the leg and foot without simultaneously making tuck stitches at the back of the leg, this being accomplished by operating the clearing cam 361 from a separate control means.

This second means is driven automatically from the main drive shaft 32 which operates the usual needle cylinder 260 through the intermediary of the main bevel gear 31. On the end of the drive shaft 32 is a small pinion engaging a gear 266 having twice as many teeth as the pinion and therefore making one revolution for every two revolutions of the needle cylinder. This gear 266 is carried on the lower arm of a bell crank lever 264 pivoted on a stud 450 on the frame of the machine and axially mounted with this gear 266 is a cam 265. When in operative position the revolution of this cam 265 in unison with the gear 266 causes vertical movement of the rod 231 by means of an operating bar 246 pivoted at one end to the upper arm of the bell crank lever 264, and its other end taking into a slotted plate 245 on the vertical rod 231. The engagement between the cam 265 and the operating bar 246 is made by means of a laterally extending pin 247 on the bar 246. The cam 265 is of such a size and shape that when its high portion is in engagement with the pin 247 the clearing cam will be held in its lowermost position so that the long latch needles will not clear their stitches.

This second control means is moved into operative position from the main drum 120 by means of drum cams 501, 502 acting against a foot 267 depending from the hub of the bell crank lever casting as shown in Fig. 1. When the depending foot 267 is on either one of the drum cams, the operating bar 246 will be lifted by the high portion of the cam 265. When the depending foot 267 rests on the surface of the main pattern drum 120, the center of the gear 266 will be below a line drawn from the center of the pinion engaging that gear to the center of

the stud 450 on which the bell crank lever is pivoted. In this position the gear 266 is still in mesh with the pinion which drives it but the high portion of the cam is too low to engage the pin 247. The length of the high portion of the cam 265 is less than one half the circumference of the cam and I prefer to so locate it that the high part of the cam lowers the clearing cam 361 while the long butt needles are passing this clearing cam. This high portion of the cam 265 is so positioned and of such length that while it will operate on the pin 247 to cause tucking on the side clocking needles, it will be out of contact with pin 247 when the long latch needles which make the narrowing marks pass the cam 361 and as a result the cam 265 cannot cause them to tuck. Since the long latch needles which made the narrowing marks on the back of the leg are located in the middle of the short butt segment of needles, no tucks are made on the back of the leg while this second control means is in operation.

If it is desired to prevent the making of tuck marks on the side of the leg during any part of the time while the narrowing mark tuck stitches are being made, two lengths of butts on the long latch needles and an extra clearing cam can be used. The long latch needles which are to make the narrowing marks have short butts and move, as already described, but the long latch needles making the marks at the side of the leg and foot have long butts and are cleared by an extra clearing cam 382 located in the path of the long butt needles just in front of the regular leading stitch cam 361. This auxiliary clearing cam 382 can be moved into and out of operative relation with the long butt needles by cam lever 487 operated by means of a cam 485 on the upper end of one of the regular thrust rods leading to the main pattern drum 120. A similar cam on a thrust rod for a similar purpose is shown and described in the patent to Robert W. Scott, No. 1,282,958, dated October 29, 1918.

The operation of my tucking attachment will now be described. Assuming that the stocking is being knit from top to toe, the welt and upper leg of the stocking are made in the regular way, the foot 267 of the bell crank lever casting being down on the surface of the main pattern drum 120.

When it becomes necessary to put in the tuck stitches for the narrowing marks on the back of the calf of the leg, the thrust rod carrying the cam 485 is moved in such a manner as to cause insertion of the auxiliary clearing cam 382 to a position where it engages the long butt needles, and simultaneously the shaft 80 turning the sprocket wheel 84 brings a series of lugs on the left side of the pattern chain 85 into engagement

with the pin 36, causing the bracket 232 to lift the vertical rod 231 every eighth revolution of the needle cylinder. This lowers the leading stitch cam 361 to the position shown in full lines in Fig. 2, and tuck stitches are made on the back of the calf of the leg by the short butt long latch needles. The trip rod 241 hits the trip wire 242 about two revolutions of the needle cylinder after each time that the rod 231 has been raised by a lug on the pattern chain, and as a result the latch 237 is freed from the bracket 232 and the clearing cam returns to its uppermost position.

After these narrowing marks on the back of the calf of the leg are finished, the auxiliary clearing cam 382 is withdrawn from contact with the high butt needles and from this point on there are no more links on the pattern chain raising the foot 235 of the bracket 232. Assuming that the tuck stitches on the side of the leg and foot are to commence at the high splice above the heel, the foot 267 on the bell crank lever casting rides on to the drum cam 501 raising the cam 265 until it is in operative position with relation to the pin 247, as shown in Fig. 1. The cam 265 will then raise the vertical rod 231 every other revolution of the needle cylinder for that part of the course during which the long butt needles are passing the leading stitch cam 361, and as a result the long butt long latch needles will not clear their stitches and tuck stitches will be made. The low portion of the cam 265 allows the vertical rod 231 to drop down each time it is raised before the long latch needles of the short butt segment of needles reach the stitch cam 361, and when the short butt long latch needles for the tuck stitches at the back of the leg reach the stitch cam, they will therefore clear their stitches and no tuck stitches will be made at the back of the stocking.

When the heel of the stocking is being made the foot 267 on the bell crank lever casting lies on the surface of the pattern drum 120 between the drum cams 501 and 502, and when round-and-round knitting is recommenced after completion of the heel, the foot 267 rides up onto the cam 502 and resumes the making of the tuck stitches on the side of the foot in a manner already described.

What I claim is—

1. A knitting machine having independent needles and a cam for the needle butts, adapted when raised to cause the latches of certain needles to clear and when depressed to cause those needles to tuck in combination with two independent automatic control means for said cam, one of said means being adapted to depress the cam for a minimum of one full revolution of the needle

cylinder the second means being adapted to depress same for a partial revolution.

2. A knitting machine having independent needles and a cam for the needle butts, adapted when raised to cause the latches of certain needles to clear and when depressed to cause those needles to tuck in combination with pattern mechanism and means operated by said pattern mechanism adapted to depress said cam during a minimum of one full revolution of the needle cylinder and a second control means operative independently of said first mentioned means adapted to depress the cam for only 15 a partial revolution.

3. A knitting machine having independent needles and a movable cam for the needle butts, adapted when raised to cause the latches of all the needles to clear and 20 when depressed to cause certain of the needles to tuck, in combination with pattern mechanism and means operated by said pattern mechanism adapted to depress said tucking cam for a minimum of one full revolution of the needle cylinder, and a second 25 means operative independently of said first mentioned means moving in time with the needle cylinder adapted automatically to depress the cam during a partial revolution.

4. A circular knitting machine having independent needles certain groups thereof having longer latches than others, a movable clearing cam adapted when raised to cause all the needles to clear and when depressed 35 to cause the long latch groups to tuck, and an auxiliary cam adapted to clear one of said long latch groups in combination with pattern mechanism and means operated by said pattern mechanism adapted automatically to depress said clearing cam during a minimum of one full revolution of the needle cylinder, a pattern drum and a second control means operative independently of said first mentioned means adapted to depress 40 said clearing cam for a partial revolution, said second control means being adapted to be thrown into and out of operative relation by said pattern drum, said auxiliary clearing cam being adapted to be put into 45 and out of operative position from said pattern drum.

5. A circular knitting machine having independent needles and a movable cam for the needle butts adapted when raised to cause the latches of the needles to clear and when depressed to cause some of the needles to tuck, in combination with a bar adapted to depress said movable cam, a bell crank lever pivotally connected to said bar, a gear 55 on said bell crank lever associated with an operating cam also on said bell crank lever, said operating cam operating to move said bar to depress said movable needle butt cam during a partial revolution of the needle cylinder, and control means comprising 60

ing a control cam adapted to move said operating cam to a position wherein it ceases to cause movement of said bar.

In testimony whereof I have signed my name to this specification.
